UNITED STATES PATENT OFFICE

1,993,281

CONVERTIBLE HINGE WINDOW

Joseph Podore, Detroit, Mich., assignor of one-fourth to Charles Noble, Detroit, Mich.

Application November 5, 1930, Serial No. 493,576
Renewed September 17, 1934

2 Claims. (Cl. 20—46)

The object of my invention is to produce a convertible window for building construction, so designed that the window sash may be raised or lowered therein by sliding within the window stops in the ordinary manner, or the sash turned inside the window frame on connected, demountable window fixtures.

Another object of my invention is to produce a combination of demountable window fixtures that may be readily installed on any ordinary sliding window, for converting the sliding sash into swinging sections by means of demountable hinged members.

A further object is to produce a combination of window fixtures that may be used for either swinging the sash members out of the window frame, or for locking the sash in various chosen positions within the frame.

A still further object is to produce a convertible hinge window, that is simple in construction, easily and efficiently installed and operated on either new or old windows and that can be manufactured at a low cost.

The several objects are attained in the preferred form by the construction and arrangement of parts more fully hereinafter set forth.

Similar parts on all drawings are marked by similar numerals or letters.

Fig. 1 is a front view of an assembled window showing the general arrangement of the convertible fixtures mounted thereon.

Fig. 2 is a horizontal sectional view taken on the line 2—2 of Fig. 1 showing the upper demountable hinge section for the top window sash.

Fig. 3 is a horizontal sectional view taken on the line 3—3 of Fig. 1 showing the hinge plate as mounted on the bottom edge of the top sash.

Fig. 4 is a horizontal sectional view taken on the line 4—4 of Fig. 1 showing the demountable hinge sections for attaching to the lower sash and converting same into a swinging section.

Fig. 5 is a sectional view taken on the line 5—5 of the Fig. 1 showing the sash locking catch and means for engaging the sash in different positions.

Fig. 6 is a vertical sectional view taken on the line 6—6 of Fig. 1 showing the relative positions of the various sash hinge members.

Fig. 7 is also a vertical sectional view taken on the line 7—7 of the Fig. 1 showing the window jamb with the hinged support members mounted thereon.

Fig. 8 is a vertical sectional view taken on the line 8—8 of Fig. 1 showing the opposite win-

dow jamb with the demountable window stops in position.

Fig. 9 is a vertical sectional view taken on the line 8—8 of Fig. 1 showing the same jamb with the demountable sections of the window stops removed, and means for attaching these sections thereto.

Fig. 10 is a front view of the assembled window showing the lower sash in its raised position and attached to the convertible hinge members, with the outer window stop section removed ready for swinging the lower sash from the window frame.

Fig. 11 is also a front view of the window with the lower sash removed, and the top sash lowered to its swing position engaging its convertible hinge members, and with both of the detachable stop sections removed.

Fig. 12 is a horizontal sectional view taken on the line 12—12 of Fig. 10 showing the lower sash swung out of the window frame.

Fig. 13 is also a horizontal sectional view taken on the line 13—13 of Fig. 10 showing both top and lower sash sections swung together outside the window frame.

Fig. 14 is another assembled front view of the assembled window showing both sash securely locked within the window frame in an opened position.

Fig. 15 is an enlarged detail view of the front side of the detachable center window stop.

Fig. 16 is a top view of the detachable center window stop shown in Fig. 15, showing its construction and means for mounting same to the window jamb.

Fig. 17 is an enlarged detail edge view of the outer detachable stop section, showing the means for attaching same to the window jamb.

In general my convertible window comprises a window frame having double sash slidably mounted therein, between parallel window stops in the ordinary manner used for window construction, but with the lower sections of the stops on one side of the window frame detachable, also demountable hinge members attached to the opposite side of the window frame, positioned to engage receiving members mounted on the sash, pivotally, if desired, at a chosen position of the sash, for swinging said sash from the window frame when the lower detachable stop sections are removed.

I will now describe more fully the detailed construction of my device, referring to the drawings and the marks thereon, and while I have illustrated my invention within an ordinary window frame, it is to be understood that the same may be applied to any window frame, and that the invention is not limited to the specific embodiment shown.

dow frame commonly used in wood buildings, it is to be understood that it applies to metal frames and sash equally as well, where the stops may be formed into demountable sections.

5 The window frame 1 comprises the side jambs *a* and *b*, the header *c* and the sill *e*, securely joined together at the corners forming a rectangular box shaped frame open on both sides. The frame 1 is provided with the finishing cas- 10 ing boards *f*, *g*, *h* and *k*, attached to the inside frame edge in the ordinary manner for sealing the window frame with the inner building wall in which it may be installed. The outer casings, or reveals *m* and *p* are likewise attached to the 15 outside frame edges in the ordinary manner for sealing the frame with the outer building wall, although the casing construction is not material to my invention. Inside the window jamb *a* are mounted window stops 2, 3 and 4, extending the 20 full length of the jamb and are fixedly attached thereto. Inside the opposite window jamb *b* is mounted a window stop 5 extending the full length of the jamb and is fixedly attached thereto, also the stub window stops 6 and 7 extending 25 along the upper section of the jamb *b* and likewise fixedly attached thereto. Joining on the lower ends of the stub stops 6 and 7 are the demountable stop sections 8 and 9 extending over the lower section of the jamb. The demountable 30 stop section 8 is preferably made of a sheet metal formed with a rectangular raised stop bar *s* of the same cross-section as the adjoining stub stop 6, and extending the entire length thereof, also provided with the side wings *t* and *v* which 35 are designed to fit flat against the window jamb. The wing *t* is extended sidewise to engage a groove *w* formed along the inner edge of the stop 5, while the wing *v* is extended sidewise to engage the edge of the lower window sash 17, the 40 lower end of the stop 8 being attached to the jamb *b* by some suitable means, preferably by engaging a sill slot *x*. Preferably inside the raised stop bar *s* is fitted a wood key *y* designed to engage the jamb groove *z* and securely hold the demountable stop 8 in a rigid position within the 45 frame, yet free to be removed therefrom. The detachable stop 9 is made of the same cross-section as the adjoining stub stop 7, and preferably connected thereto by a bevel joint end. The 50 stop 9 is securely attached to the jamb *b* by the thumb screws 13 passing through the stop and engaging metal casing nuts 14, countersunk and fixedly mounted within the jamb wall *b* by suitable screws 15. The nuts 14 may be made ad- 55 justable on the attaching screws by slotted screw holes formed therethrough, and providing means for adjusting the stop 9 to the inclosed sash 17 when assembled. Any convenient form of thumb screw 13 will operate, but a type that will be per- 60 manently retained within the stop 9 is preferred. All of the window stops are positioned on the jambs parallel to each other, and so spaced as to receive and fit the sash 16 and 17 slidably mounted therein. The length of the demount- 65 able stops 8 and 9 is slightly greater than the sash length to provide sufficient clearance between the ends of the stub stops 6 and 7 and the window sill for easily swinging both sash there- 70 through. The frame header *c* also is provided with corresponding stop members 10, 11 and 12, extending the full length thereof and are fixedly attached thereto as in any ordinary window frame.

Along the window stop 4, on the opposite side 75 of the frame, are mounted two demountable

hinge members 18 and 19, fixedly attached to the stop 4 by suitable screws 20, but providing one free hinge wing *i* of each member, free to swing on its respective hinge joint. The hinge members 18 and 19 are positioned opposite the lower sash 17, preferably one at or near each end of said sash, and adjusted therewith so that the hinge wing *i* of both hinge members will swing and fit flat against the inner face of the sash rail. At the top edge of the free wing *i* on each hinge member 18 and 19 is formed a slotted recess 21, and which will engage and receive therein the projected screws 22 of the sash 17, if said sash be slightly lifted to bring the screws 22 above the hinge wing slots before said hinge wings are turned thereto and the sash then lowered therein, as shown in Fig. 10. The screw heads 22 being projected from the face of the window sash 17 just sufficiently to allow the free hinge wings *i* to be inserted thereunder, and provided a rigid hinge connection to the sash when the screws are lowered in the hinge slots 21 for swinging the sash 17 inside the window frame when the demountable stop 9 is removed from the opposite casing jamb, as illustrated in Fig. 12. Likewise on the window stop 3 are mounted two hinge blocks 23 provided with fixed hinge pins 24, said hinge blocks being securely attached to the stop by suitable screws, and are also positioned opposite the demountable stop 8 near opposite ends thereof. Mounted on opposite ends of the sash 16, and in true alignment with the hinge pins 24, are the hinge bearings 25 and 26, each fixedly attached to the sash by suitable screws, and positioned thereon to engage the hinge pins 24 of the hinge blocks 23 when the sash 16 is lowered to a position opposite the demountable stop 8, as shown in the Fig. 11, and the sash 16 may also be swung thereon inside the window frame when the detachable stop 8 is removed from the jamb *b*, as illustrated in Fig. 13, thus providing means for turning both sash inside the frame simultaneously, as may be desired, for either repairing or washing, and may then be quickly and easily re-converted back to the sliding window by simply swinging the respective sash back in place and replace the demountable stops 8 and 9.

The demountable hinge 18 is formed with an enlarged circular recess 27 through the free wing *i*, for receiving therethrough the projected screw head 28 when it is desired to raise the sash 17 for ventilation, as shown in Fig. 14, and at the same time locking the sash in that position, the screw head 28 passing through the hinge wing will prevent any movement of the sash in either direction. The position of the screw 28 may be varied and adjusted as desired, depending upon the size of opening required for ventilation.

On the top edge of the sash 17 is mounted a small lock clip 29, pivotally attached thereto by the screw 30, and positioned thereon to engage various projected screw pins 31 as may be mounted on the inside face along the sash rail of the upper sash 16, allowing the top sash 16 to be lowered to various positions and securely locked therein, as illustrated in Figs. 1, 10 and 14.

The sash may be mounted within the window 70 casing frame, if desired, together with the ordinary window weights, ropes and pulleys, and various types of weather-stripping, although neither of these are material to my invention which is confined to the convertible sliding and 75

swinging sash, and the various required mounting therefor.

While I have illustrated my convertible window as applied to a simple type of wood window frame, it is apparent that the invention is capable of various modifications in both design and construction, without departing from the spirit of my invention, and I claim the design as shown together with modifications thereof as 10 may be substantially a substitution of parts therein shown.

Having fully described my convertible hinge window, what I claim as my invention and desire to secure by Letters Patent is:

- 15 1. A convertible window comprising a window casing with window sash slidably mounted therein, said casing having detachable stop sections, two leave hinge members arranged in pairs and mounted on the casing member, fixedly attached 20 thereto, said hinge members having one free leaf formed with a slotted top edge and provided with a circular hole therethrough beneath said slot and positioned to turn flat against the adjacent sash face, headed pin members 25 fixedly mounted at various positions along the respective sash face, positioned to engage the casing hinge leaf slot or hole at various sash positions, and at one chosen position capable of swinging the sash clear from the window 30 casing.
2. A convertible window comprising a window casing formed with removable sash stop sections, and having sash sections slidably mounted therein, a pair of two leaf hinge members mounted on the casing side wall adjacent the lower sash and fixedly attached to the casing wall by screws, said hinge members having one free leaf slotted at the top edge and provided with a circular hole therethrough beneath said slot and so positioned to be turned flat against 10 the adjacent sash face, headed pin members fixedly mounted at various positions in the lower sash face positioned to engage the casing hinge slot or hole at various sash elevations, one of which will allow said sash to swing clear from 15 the window casing, fixed hinge members with vertical hinge pin fixedly and rigidly attached to the lower section of the casing wall center sash stop parallel to the inner face of the upper window sash, hinge engaging members with vertical 20 pin socket fixedly mounted on the inner face of said upper sash positioned to engage with the said center sash stop hinge pin when the upper sash is lowered thereon for swinging said sash from the window, stop pins mounted along the 25 upper sash inner face, and a stop block pivotally mounted on the lower sash edge to engage therewith when any one of the mounted stop pins are lowered thereon.

JOSEPH PODORE. 30
